SURGICAL SUTURE REMOVER

William Glenn Allen, Jr., 1811 Floyd Ave.,
Richmond, Va. 23220

Filed Oct. 18, 1973, Ser. No. 407,471

Term of patent 14 years

Int. Cl. D24—02

U.S. CL. D83—12 R

FIG. 1 is a perspective view of a surgical suture remover showing my new design;

FIG. 2 is a cross-sectional view taken on line 2-2 of FIG. 1;

FIG. 3 is a cross-sectional view taken on line 3-3 of FIG. 1, and

FIG. 4 is a cross-sectional view taken on line 4-4 of FIG. 1.

I claim:

The ornamental design for a surgical suture remover, as shown.
